(57) CLAIM

I claim the ornamental design for a shoe box, as shown and described.

DESCRIPTION

FIG. 1 is a front elevation view of the shoe box showing my novel design;

FIG. 2 is a rear elevation view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof of the invention in use.
The broken lines shown in FIGS. 1, 2, 3, 4, 6 and 7 are an illustration of a typical bottom of my shoe box and form no part of the claimed design.
